ABSTRACT OF THE DISCLOSURE

Delivery apparatus having a magazine for containing stacked mattress handles and including a pair of release cams engageable at opposite sides of the stack to lift it off the lowermost handle in the stack to release said handle, whereby it can slide under gravity for delivery to a handle attaching mechanism.

The invention relates broadly to automatic machinery for attaching mattress handles to webbing which is subsequently utilized in the manufacture of mattresses, the invention having particular reference to improved apparatus for delivering handles to the specific handle attaching facilities of such machinery for attachment as aforesaid.

In general, such machinery usually takes the form of a press including at least three facilities, namely, means for advancing the webbing; means for attaching handles to the webbing, and mechanism for delivering handles to the attaching facilities for attachment to the webbing.

In particular, the invention is concerned with improvements in the latter facility, namely, mechanism for delivering the handles to the attaching facilities of the machinery.

Mattress handles as herein contemplated are conventionally moulded of plastics in moulds having multiple cavities so that the usual product yielded by such a mould comprises a number of handles interconnected together by short sprues linking and forming them into a gang or assembly of handles as is known by those in the art.

In accordance with current practices, the individual handles are respectively detached from the assemblies and attached at measured intervals to the webbing which moves past the specific attaching mechanism; the webbing being usually subdivided into individual lengths after the said handles have been attached thereto for later incorporation into mattresses as the side walls or "borders" thereof, although this latter step has no bearing on the present invention.

As has been indicated, a main object of the invention is to provide improved mechanism for delivering handle assemblies to the attaching facilities of machinery as aforesaid and a somewhat more specific object is to provide such mechanism having a magazine for a stack of handle assemblies as well as means for transferring successive assemblies individually from the magazine to the attaching facilities of the press which may also be equipped with means for severing individual handles from the assemblies aforesaid although such means do not constitute part of the present invention.

It may be useful to observe at this juncture that each of the handles contemplated by the invention is equipped with fastening elements by which it is attached to the mattress border; such fastening elements being often pre-installed in the handles before the latter reach the attaching facilities of the machinery and, usually, are so installed even before the handle assemblies are loaded into the instant delivery mechanism. Each said fastening element includes a complement of sharpened prongs which project markedly through the handles when the said fastening element is installed therein as aforesaid. Resultantly, when several handle assemblies are stacked in the magazine as

2

above indicated, it is not uncommon for some of them to become enmeshed in the fastener prongs projecting from others to the extent that force may be required to separate them.

Some of the other objects of the invention are, therefore, to provide means for delivering successive handles to handle attaching machinery as aforesaid, including mechanism for disengaging and separating individual handle assemblies from the stack contained in the magazine for transfer to the attachment facilities of the machinery.

To provide such mechanism with a simple but effective escapement for this purpose;

To provide such escapement with means insertable between two handle assemblies to free at least one of them for transfer as aforesaid, said insertable means being further capable of prying said assemblies apart when and if necessary, and, in the present embodiment at least,

The invention further seeks to provide structure which will permit transfer of the handles as aforesaid by gravity.

A still further refinement contemplated by the invention comprises means for sensing and responding to demand—by the attaching machinery—for handles, and the provision of the instant delivery mechanism equipped with such demand sensing and answering means is also an object of the invention.

It will, of course, be recognized as yet another and obvious object of the invention to provide handle attaching machinery equipped with the instant handle delivering mechanism.

In accordance with the invention, there is provided means for delivering successive handles to machinery for installing such handles on mattress walls comprising a magazine for a stack of handle assemblies disposed in registering frictional interengagement with each other; means for transferring the leading handle assembly at one end of the stack from said magazine to the said machinery; seating upon which the stack is disposable with the said leading assembly in position for transfer as aforesaid, said transfer being ordinarily inhibited by the frictional interengagement of the leading assembly with the next following assembly; an escapement cyclically operable to disengage the said leading assembly from the next following assembly and to free it for transfer as aforesaid, said escapement being thereafter operable to redispone the remainder of the stack on said seating with the said next following assembly in leading position, the operation of the escapement to disengage the leading and following assemblies and to redispone the remainder on the seating as aforesaid constituting a single cycle of operations, and mechanism for sensing a demand for handles and for initiating a single cycle of operations to procure transfer of at least one handle assembly in response to said demand.

The foregoing and other more or less broad objects of the invention are achieved by means of the elements, parts and principles constituting the invention set forth, a preferred embodiment whereof is set forth in the hereinafter following description and illustrated by way of example only in the hereunto annexed drawing wherein like reference devices refer to like parts of the invention and wherein:

FIG. 1 is a more or less diagrammatic view of a handle attaching press shown in side elevation with the instant handle delivering mechanism associated therewith;

FIG. 2 is an isometric view of the upper structure of the press shown in FIG. 1 with various portions thereof broken away to reveal hidden details;

FIG. 3 is a rear elevational view of the magazine forming parts of the instant invention, particularly illustrating parts of the escapement aforesaid;

FIGS. 4, 5 and 6 are a series of fragmentary views

showing certain parts of the escapement mechanism at different stages of operation, and

FIG. 7 is an isometric view of a handle as contemplated by the invention with fastening elements installed therein.

The various objects of the invention are more particularly realized by the provision of a magazine for stacked handle assemblies and transferring means which may include a track communicating between said magazine and the attaching facilities of the press. In addition, the invention contemplates an escapement for disengaging the leading handle assembly at the forward end of the stack in the magazine to free it for transfer along the said track from the magazine to the attaching facilities aforesaid. Such disengagement of the leading handle assembly is, preferably, effected by moving the next following assembly and the remainder of the stack away from the leading handle assembly. When said leading handle assembly has been duly transferred, the stack may then be relocated in the magazine with the said next following assembly in leading position and becoming the new leading handle assembly.

FIG. 1 of the attached drawing is chiefly intended for orientation purposes to illustrate the relationship of the present invention to the handle attaching machinery or press of the prior art which is denoted in the drawing by the reference device P; the numeral 2 being intended to designate generally the attaching facilities of the press which may comprise a pair of setting dies by which individual handles 4 of FIG. 7 are secured to webbing 6 moving across the bed 8 of the press P therebelow. This structure is not part of the invention nor, in a broad sense, is the chute 10 shown in this view constituting the specific track by which handle assemblies 14 are, in this embodiment, successively transferred to the handle attaching facilities 2 aforesaid.

In the present embodiment of the invention, said chute 10 includes a track providing a glide surface for the handle assemblies 14; said track being constituted by symmetrical rails 16-16 which are joined together in parallel relation by ties 18; being spaced so that the widened end terminals 20-20 of the respective handles 4 will ride the said rails 16-16 when a said handle assembly 14 is being transported along chute 10.

The chute 10 aforesaid which forms part of the transfer means in this embodiment communicates between the machinery or press P and the magazine M in which the handle assemblies 14 are stacked for respective delivery to the attaching facilities 2 of the machinery P.

For the sake of clarity, it should be observed that the letter S herein denotes a stack of two or more handle assemblies 14 contained in said magazine M and resting on seating 24 which merges with chute 10 so that the specific handle assembly 14 actually occupying seating 24 is in leading position and poised to commence its travel from said seating 24 along chute 10 to the attaching facilities 2 of the machinery P. Each handle assembly 14, of course, comprises a plurality of handles 4 ganged or connected together by sprues 5.

Said specific handle assembly 14 actually occupying seating 24 is herein distinguished as the "leading" handle assembly at the forward end of stack S and is identified by the reference device 14a; the specific handle assembly 14 next succeeding it being herein more particularly identified as the next following handle assembly 14b. It will be obvious that as each leading handle assembly 14a embarks on its journey towards the press P, said next following assembly 14b moves up to the next position in line for transfer and hence becomes eligible to assume the place and identity of the erstwhile leading handle assembly 14a; its follower being thereafter identifiable as the next following assembly 14b.

In the present embodiment, the handle assemblies 14 in stack S are transferred from magazine M to press P by

gravity and said magazine M is, therefore, stationed at a level above that of the attaching facilities 2; the chute 10 connecting it to press P being, resultantly, downwardly inclined. In this case, the handle assemblies 14 are, therefore, preferably stacked more or less horizontally in magazine M whereby the bottom of stack S becomes its forward end and the handle assembly 14 at that end becomes the leading handle assembly 14a.

The magazine M is equipped with walls and other elements providing containment for all of the handle assemblies 14 stacked therein above the level of the leading assembly 14a thereby providing access openings 25-25 at the side of magazine M and an escape opening 26 at the front of the magazine through which said leading handle assembly 14a makes its exit from magazine M.

As has been stated, the seating 24 merges with rails 16-16 of chute 10 so that leading handle assembly 14a in magazine M may make the transition from seating 24 to chute 10 virtually without impediment. To facilitate such transition, the magazine M is tilted forwardly towards chute 10 while gliding surfaces of rails 16-16 and seating 24 on which the respective handle assemblies 14 ride on their downward journeys to the press P are rendered relatively friction free by a high polish. Resultantly, the leading handle assembly 14a makes its exit from seating 24 is at all times biased for transfer.

However, it will be appreciated that being at the bottom of stack S, said leading handle assembly 14a may be frictionally interengaged with the next following handle assembly 14b at least, whereby its escape through exit opening 26 is normally inhibited.

To free said leading handle assembly 14a for transfer as aforesaid, the invention provides elongated rockers 30 each rotatably supported on an axle 36 trunnioned on each side of the stack S with means (to be described) at the back of the magazine M for operating said rockers 30-30 to effect disengagement of the leading handle assembly 14a from the next following assembly 14b, and the remainder of the stack S, to free the said leading handle assembly 14a for transit down chute 10 to press P; said rockers 30-30 being thereafter operable to reposition the stack S on seating 24 with the next following handle assembly 14 being in leading position as hereinbefore described.

In its essential features, each said rocker 30 is journaled for rotation or oscillation about an axis paralleling the sides of magazine M. Moreover, each said rocker 30 is of cam-like transverse cross-section and has a lip 32 which is parallel to its axis and spaced therefrom so that said lip 32 describes an arcuate orbit when the rocker 30 is oscillated.

In its neutral position, see FIG. 4, each rocker 30 is turned so that it is at one side of and wholly clear of stack S with its lip 32 lowered. In addition, it is dimensioned and situated so that when it is turned on its axis in an appropriate direction, its lip 32 will intervene through the proximal access opening 25 between the leading and following handle assemblies 14a and 14b in magazine M, after which continued rotation of rocker 30 will cause its said lip 32 to engage said next following assembly 14b and to lift it (and the remainder of stack S) off the leading assembly 14a, thereby disengaging the two handle assemblies from each other and freeing the leading assembly 14a for transfer.

The rockers 30-30 operate in synchronism as will be understood and when the leading assembly 14a has duly vacated seating 24, they are turned back toward neutral position in the course of which they replace stack S on seating 24 with the previously next following handle assembly 14b in leading (14a) position.

To meet the exigencies created by the enmeshing of the next following handle assembly 14b with the prong fastener element 34 of the leading assembly 14a, said lip 32 is dimensioned and given the form of wedging for pry-

ing apart, if need be, said leading and following handle assemblies 14a and 14b.

As stated hereinbefore, there is provided means at the rear of the magazine for operating the rockers 30-30. Such means conveniently takes the form of a mechanical linkage interconnected between the ends of the rocker axles 36 together with a fluid pressure actuated piston and cylinder assembly 38, the piston 40 of which acts directly upon the linkage to cause rotation of the rockers 30-30.

More specifically, the linkage comprises two short lever arms 42-42, each mounted fast, at one of its ends, with a rocker axle 36 and each having its free end freely pivotally connected to the respective ends of an intermediate bridging link 44. A further short lever arm 46 is also mounted at one of its ends fast with one of the axles 36.

Fluid pressure actuated piston and cylinder assembly 38 is mounted alongside the magazine M at its back edge in such manner that the piston 40 can move vertically 20 to bear upon the lever arm 46 and consequently rotate the rockers 30-30 via the interconnection between arms 42, axles 36 and link 44. In the construction shown, downward movement of the piston 40, i.e.: extension thereof, will rotate the rockers 30-30 simultaneously to disengage the leading handle assembly 14a from the next following assembly 14b.

Such rotation of the rockers 30-30 with the consequent release of the leading handle assembly 14a for transfer as aforesaid, see FIGS. 5 and 6, and subsequent return of the rockers to their initial position upon retraction of the piston 40 constitutes a single cycle of operations.

Also, in accordance with the invention, there is provided mechanism for sensing a demand for handles, for attachment to the webbing as hereinbefore described, and for initiating a single cycle of operations to procure handle transfer as aforesaid.

Said sensing mechanism includes a micro-switch 48 (see FIG. 2) mounted behind one of the guide rails 16 in such a position that a handle assembly 14 in the chute 10 will engage the micro-switch 48 and close it. As is shown in FIG. 2, the switch 48 is engaged by one of the terminal portions 20 of each successive handle 4 as the handle assembly 14 passes down the chute. Closure of the micro-switch closes an appropriate electrical circuit (not illustrated) which, in turn, controls the aforesaid piston and cylinder assembly 38 to retain the piston 40 in its retracted position.

When the last handle of a handle assembly 14 in the chute has passed over the micro-switch 48 as the handle assembly moves down the chute, the micro-switch is permitted to open under spring pressure. This opening of the switch opens the aforesaid electrical circuit to actuate the piston and cylinder assembly 38 to cause extension of the piston 40 with the subsequent rotation of the rockers 30-30 through the positions shown in FIGS. 4-6 to disengage the leading handle assembly 14a from the next following assembly 14b. This disengagement, as hereinbefore described, permits the leading handle assembly 14a to slide under gravity down the chute 10 until the foremost handle of this transferred assembly slides into abutting engagement with the rearmost handle of the preceding assembly 14 already in the chute 10. At this position, as shown in FIG. 2, the said foremost handle of the transferred handle assembly will engage the micro-switch 48 to close it and cause retraction of the piston 40 with the consequent return of the rockers 30-30 to their initial position as shown in FIG. 4. At this time, what was the next following assembly 14b is permitted to drop into position within the magazine M upon seating 24 to become the next leading assembly 14a ready for transfer as aforesaid when a next single cycle of operations is initiated.

It will be appreciated that the hereinbefore described

embodiments of the invention have been selected solely for the expository purposes hereof and should not be construed in a limiting sense; various modifications being readily suggestible to those skilled in the art and the true scope of the invention being restricted only by the claims hereinafter set forth.

What I claim is:

1. Means for delivering successive handles to machinery for installing such handles on mattress walls comprising:

a magazine for a stack of handle assemblies disposed in registering frictional interengagement with each other;

means for transferring the leading handle assembly at one end of the stack from said magazine to the said machinery;

seating upon which the stack is disposable with the said leading assembly in position for transfer as aforesaid, said transfer being ordinarily inhibited by the frictional interengagement of the leading assembly with the next following assembly;

an escapement cyclically operable to disengage the said leading assembly from the next following assembly and to free it for transfer as aforesaid, said escapement being thereafter operable to redispose the remainder of the stack on said seating with the said next following assembly in leading position, the operation of the escapement to disengage the leading and following assemblies and to redispose the remainder of the seating as aforesaid constituting a single cycle of operations, and

mechanism for sensing a demand for handles and for initiating a single cycle of operations to procure transfer of at least one handle assembly in response to said demand.

2. Delivering means as set forth in claim 1 wherein said escapement includes:

means insertable between said leading and next following assemblies for effecting disengagement of the said leading assembly and freeing it for transfer as aforesaid;

said escapement being operable thereafter to withdraw said insertable means to a neutral position following redisposition of the said next following assembly in leading position on the said seating.

3. Delivering means as set forth in claim 1 wherein said escapement includes:

wedging insertable between said leading and next following assemblies for prying them apart for effecting disengagement of the said leading assembly and freeing it for transfer as aforesaid;

said escapement being operable thereafter to withdraw said wedging to a neutral position following redisposition of the said next following assembly in leading position on the said seating.

4. Delivering means as set forth in claim 1 wherein said escapement includes:

eccentric wedging means for prying apart said leading and next following assemblies, said wedging means being provided with trunnions about which it is pivotally rotatably mounted;

said wedging means being insertable between said leading and next following assemblies for effecting disengagement of the said leading assembly and freeing it for transfer as aforesaid;

said escapement being operable thereafter to withdraw said wedging means to a neutral position following redisposition of the said next following assembly in leading position on the said seating.

5. Delivering means as set forth in claim 1 wherein said escapement includes:

means insertable between said leading and next following assemblies on opposite sides of said stack for effecting disengagement of the said leading assembly and freeing it for transfer as aforesaid;

said escapement being operable thereafter to withdraw said insertable means from both sides of said stack to a neutral position following redisposition of the said next following assembly in leading position on the said seating.

6. Delivering means as set forth in claim 1 wherein said escapement includes:

elongated cams insertable on opposite sides of said stack between said leading and next following assemblies for effecting disengagement of the said leading assembly and freeing it for transfer as aforesaid; said escapement being operable thereafter to withdraw said cams from both sides of said stack to a neutral position following redisposition of the said next following assembly in leading position on the said seating.

7. Delivering means as set forth in claim 1 wherein said magazine is oriented to contain said handles in stacked superposed relation with the lowermost assembly in leading position; the transferring means comprising a chute merging with and forming a continuation of said seating.

8. Delivering means as set forth in claim 7 wherein

said escapement includes means for raising said next following assembly off the lowermost assembly, freeing the latter for transfer as aforesaid and for thereafter lowering said next following assembly on the said seating in leading position.

5 9. Delivering means as set forth in claim 8 wherein said magazine includes containment for the stack of handle assemblies above the leading assembly; said magazine having an outlet for the said leading handle assembly between the seating and the transfer means.

10 10. Delivering means as set forth in claim 9 wherein said magazine is disposed at a level above that of the attaching machinery and is tilted to permit transfer of the said handle assembly under the force of gravity.
